UNITED STATES PATENT OFFICE.

HERMAN LIPSTREUER, OF CLEVELAND, OHIO.

WINDOW-FRAME CONSTRUCTION.

Application filed August 20, 1923. Serial No. 658,203.

To all whom it may concern:

Be it known that I, HERMAN LIPSTREUER, a resident of the city of Cleveland, in the county of Cuyahoga and State of Ohio, and 5 a citizen of the United States, have invented certain new and useful Improvements in Window-Frame Constructions, of which the following is a specification.

This invention relates to window frames 10 and the like, and to the means for forming such casings in masonry walls.

In applying the invention to the repairing of old windows where wooden casings have been used, it is seldom found that the 15 upper plate or sill is decayed; water dripping down usually rots the lower plate first, as well as the lower ends of the side members. Under these conditions the lower sill and side members are replaced with concrete construction and the new upper sill 20 may be used or the old one can be employed in the manner herein after set forth.

Frames constructed in accordance with this invention may also be used in new construction work; the frames are first molded and then the masonry wall is constructed around them. The frames for this work 25 may be molded and furnished as building material or they may be molded in place 30 in the wall as it is being constructed.

The primary object of this invention is to improve the construction of such casing or 35 frame members and the manner of forming them is a wall.

Further objects and details of the invention will be disclosed in the accompanying drawings, forming a part of this specification, and set forth in the following description, and claimed.

In the drawings, like characters of reference are used to designate the same parts in the three figures in which,—

Figure 1 is a perspective view of a window casing made in accordance with this 45 invention with the masonry wall of a building extending from it,

Figure 2 is a cross sectional view on line 2—2 of Figure 1, and

Figure 3 is an elevation of a wall showing 50 the process of forming such a casing in a finished wall.

Referring to the drawings, in Figure 1, a masonry wall 10 is shown around a window frame 11 to which a window sash 12

is hinged at 13 so as to swing rearwardly 55 upward from the upper sill 14 of the frame 11.

The frame 11 comprises an upper sill 14, preferably made of wood, and lower sill 15 and side members 16 formed of concrete having U-shaped reinforcing rods 17 formed in the concrete members with their ends secured in the upper sill member. Each of the side members 16 is formed with an extending tongue 18 which is adapted 65 to be received in grooves 19 in the masonry wall. The inner, or rear side, of all the members as shown in Figure 1, is rabbeted at 20 for the reception of the window sash 12 in the usual manner.

Preferably, such frames are molded in quantities. The wooden upper sill 14 has the U-shaped rods 17 secured to it and is placed and secured in a mold having corresponding configurations to the finished 70 frame for receiving the concrete which is then added. Then the complete frames are set in position in the wall, and the latter is built around it. However, the frames may be constructed in the walls of the building, 80 using the window opening in the walls as the outer form of the mold and positioning the upper sill 14 with the rods 17 and other form members in the opening for receiving the concrete which may be poured in from 85 the top. In this case the upper sill can be left off until after the concrete is poured and afterwards secured in place on the upper ends of the rods 17.

In Figure 3 a method of molding such 90 frames in an opening in a wall is shown. The wall 10 having the usual window opening which may have been formed therein during the process of construction or made later, is provided with grooves 19 as heretofore set forth. In repairing old windows it is sometimes found that the openings are already provided with such grooves when the old wooden sides are removed; otherwise they may be formed with mason's 95 tools. It will here be noted that although the other edges of the openings may be provided with such grooves for tongue members, they are unnecessary and are therefore not shown; the tongues are not needed at 100 the top or bottom of the frame as the side tongues together with the top plate are sufficient.

The upper sill 14 is secured in place in the window opening, or in the case of repairing of windows the old upper sill may be used again, and merely the side and bottom plates are removed from the opening. The mold members 21 and 22 are positioned in the opening beneath the upper sill and the reinforce rods 17 are enclosed in the mold members having been first placed in position with their upper ends inserted in the sill 14. The outer edges of the molds remain open at the three sides of the frame and the concrete is packed into them through these three continuous open edges until they are filled. When the concrete has set, the molds are removed, and the reinforced frame is complete, having sides and bottom of cement and its wooden top plate. Such frames are especially adapted for window sashes that are to be hinged to the top plate or sill, but may, possibly, be used when the sashes are to be hinged to one of the side members. The advantage of a frame having one member to which a sash can be hinged with the remaining members of reinforced concrete secured to the first member will readily be seen as well as other advantages of the construction and process which has been herein set forth.

This invention is not limited to the embodiments herein before described, and shown in the drawings, for the purpose of giving examples or illustrations of the employment of the invention, for it will be obvious that wide departure from the details as set forth may be made without departing from the spirit and scope thereof in the claims.

What is claimed as the invention and is desired to be secured by Letters Patent is;—

1. The combination of a masonry wall having an opening therein, a rectangular frame having one side of wood and the remaining sides of reinforced concrete positioned in said opening, the reinforcing element extending beyond the concrete and secured in the wood side and projections from

said frame structure engaging with the wall for locking the frame in position.

2. A rectangular frame comprising a 50 wooden member forming one side of the frame, U-shaped reinforcing members having their free ends secured in the wooden member adjacent to its ends, and concrete molded around said reinforcing members so 55 as to complete the frame forming the other sides thereof.

3. A window casing comprising a frame having a wooden upper sill member, a U-shaped reinforcing rod having its free ends 60 secured to said sill adjacent to the ends thereof, side members of concrete molded around said reinforcing member engaging said sill and provided with outwardly projecting tongue members, and a lower sill of 65 concrete molded around the reinforcing member forming a continuous integral concrete structure with said side members.

4. The method of repairing window casings in a masonry wall comprising the removing of the old lower wooden sill and side members thereof, securing reinforcing rods to the upper sill member of the casing so as to extend through the space occupied by the members which were removed, and the placing of concrete around said rods in engagement with the window opening in the wall and molding the same to form a new casing member.

5. The method of forming a window 80 casing in a window opening in a masonry wall comprising the positioning of an upper sill member in the opening with a reinforcing member secured thereto so as to extend around the opening in the space to be occupied by the side and lower sill members of the casing, and the placing of concrete around said reinforcing member in engagement with the window opening in the wall and molding the same to form the sides and 85 lower sill of the casing.

In testimony whereof I hereunto affix my signature.

HERMAN LIPSTREUER.
